COMBINATION AUTOMATIC CLOTHES WASHER AND DRIER

John F. Horvath, Milwaukee, Wis., assignor to Vamco Corporation, Brooklyn, N.Y., a corporation of New York

Filed Aug. 1, 1962, Ser. No. 71,131

Term of patent 14 years

(Cl. D49—1)

FIG. 1 is a front perspective view taken from the left side and top of a combination automatic clothes washer and drier embodying my new design;

FIG. 2 is a somewhat enlarged fragmentary side elevational view of the front panel portion taken from the left side thereof;

FIG. 3 is a further enlarged fragmentary section taken along the line 3—3 of FIG. 1;

FIG. 4 is another enlarged fragmentary section taken along the line 4—4 of FIG. 1; and

FIG. 5 is an enlarged fragmentary section taken along the line 5—5 of FIG. 1.

The dominant features of my design reside in the portions shown in full lines.

I claim:

The ornamental design for a combination automatic clothes washer and drier, substantially as shown and described.
